CLAIM

The ornamental design for a litter scoop, as shown and described.

DESCRIPTION

FIG. 1 is a front perspective view of a litter scoop according to our new design;

FIG. 2 is a rear perspective view thereof;

FIG. 3 is top view thereof;

FIG. 4 is a bottom view thereof;

FIG. 5 is a front elevation view thereof;

FIG. 6 is a rear elevation view thereof; and,

FIG. 7 is a right side elevation view thereof, the left side elevation view being identical.
